UNITED STATES PATENT OFFICE.

CHARLES E. MILLER, OF CHICAGO, ILLINOIS.

LOCOMOTIVE ARCH.

Application filed February 7, 1923. Serial No. 617,489.

To all whom it may concern:

Be it known that I, CHARLES E. MILLER, a citizen of the United States, and resident of Chicago, in the county of Cook and State 5 of Illinois, have invented certain new and useful Improvements in a Locomotive Arch, of which the following is a specification.

My invention relates to baffling devices for locomotives and particularly to a novel 10 side brick construction.

It has been common in the art to provide a plurality of longitudinally extending inclined tubes within the fire-box and to place thereon suitably shaped bricks, the marginal 15 bricks resting on an arch tube and leaning against the fire-box side sheet in an upwardly inclined position. Due to variations in the width of the space within which the side bricks are placed, the angle of inclination will vary and in instances where the 20 inclination is less abrupt there is a strong tendency to force the tube laterally. As this would tend to elongate the tube, it is not unusual to find that leakage occurs at the 25 points of engagement of the tube with the boiler.

One of the objects of my invention is to provide a construction in which this wedging 30 tendency is eliminated entirely or partly, the result being secured by utilizing an L-shaped side brick, the short arm of which rests upon an arch tube and abuts an adjacent 35 intermediate brick and the long arm of which extends horizontally and abuts the side sheet. Any wedging tendency is transmitted to the body of the arch consisting of so-called middle bricks and the possibility 40 of forcing the arch tubes out of line is eliminated.

The invention will be more readily understood by reference to the accompanying drawing, in which:

Figure 1 is a transverse vertical section through a locomotive fire-box equipped with 45 an arch constructed in accordance with my invention; and

Figure 2 is an end elevation of a transverse row of bricks, showing the arch tubes and side sheet in section.

In the drawing it will be seen that the side sheets of the fire-box are indicated at 50 10 and the arch tubes, of which four are shown, at 11. The space between adjacent arch tubes is closed by so-called middle bricks 12, the form of which is well known and will not be described in detail except to

explain that the bricks are provided at their marginal edges with grooves shaped to conform to the periphery of the arch tubes, with the result that the bricks are fitted 60 down between the adjacent tubes.

The side bricks are of peculiar construction, being of angular or L-shape in end elevation. The short arm 13 is provided with a longitudinal groove 14 conforming 65 to the curvature of the outer arch tube. The long arm 15 of the brick extends horizontally in a plane above the middle bricks and the outer end 16 abuts squarely against the side sheet 10. It will be noted that at 70 the point 17 the short arm 13 of the side brick abuts the end of the adjacent middle brick 12 and that any wedging tendency which may be exerted by the side brick is transmitted to the adjacent middle brick 75 80 and is thus distributed over the entire series of arch tubes. The long arm 15 is preferably thinned toward its outer end and the principal body of material is in the vertical arm and in the bend; thus the major component of the force exerted by the side brick is vertical. In order to avoid all possibility of wedging action on the outer arch tube, it will be noted that I provide a clearance space 18 in the groove 14 so that normally 85 the lateral component of force is exerted directly against the adjacent middle brick 12.

The exact shape of the brick is immaterial except however in that it is desirable 90 that a horizontal center line through the long arm 15 should extend above the plane of the intermediate bricks. The distance above this plane is more or less immaterial and will be governed by the exigencies of 95 each case. I do not therefore, wish to be limited except as indicated in the appended claims.

I claim:

1. In a locomotive arch, the combination 100 with arch tubes and side sheets, of bricks laid upon and closing the space between adjacent tubes, and an L-shaped brick having arms of unequal length the short arm extending vertically and resting upon an out-side arch tube and the long arm extending horizontally and abutting a side sheet.

2. In a locomotive arch, the combination 110 with arch tubes and side sheets, of bricks laid upon and closing the space between adjacent tubes, and an L-shaped brick having arms of unequal length the short arm ex-

tending vertically and resting upon an outside arch tube and abutting an intermediate brick and the long arm extending horizontally and abutting a side sheet.

3. In a baffle construction, the combination with the side sheets and arch tubes of a fire-box of bricks supported between adjacent arch tubes, and side bricks of angular form in end elevation, one arm thereof extending vertically and provided with a groove in one margin thereof, said groove being formed on a radius greater than that of the arch tube with which the groove cooperates whereby the brick rests upon the top of the arch tube without contacting with the side portion thereof, a portion of the body of said short arm resting against the end of an adjacent brick, the long arm of the side brick extending horizontally in a plane above said adjacent brick and contacting the side sheet.

4. In a baffle construction, the combination with the side sheets and arch tubes of a

fire-box of bricks supported between adjacent arch tubes, and side bricks of angular form in end elevation, one arm thereof extending vertically and provided with a groove in one margin thereof, said groove being formed on a radius greater than that of the arch tube with which the groove cooperates whereby the brick rests upon the top of the arch tube without contacting with the side portion thereof, a portion of the body of said short arm resting against the end of an adjacent brick, the long arm of the side brick extending horizontally in a plane above said adjacent brick and contacting the side sheet.

Signed at Chicago, Ill., this 5th day of February, 1923.

CHARLES E. MILLER.
